UNITED STATES PATENT OFFICE.

LOUIS GOODMAN, OF NEW YORK, AND ARTHUR GOLDSTEIN, OF BROOKLYN, NEW YORK.

DISPLAY DEVICE.

Application filed February 27, 1922. Serial No. 539,626.

To all whom it may concern:

Be it known that we, LOUIS GOODMAN and ARTHUR GOLDSTEIN, both citizens of the United States, and residents, respectively, 5 of the city of New York, borough of Manhattan, in the county and State of New York, and of the city of New York, borough of Brooklyn, in the county of Kings and State of New York, have invented new and 10 useful Improvements in Display Devices, of which the following is a full, clear, and exact description.

This invention relates to display devices.

Salesmen find it more or less inconvenient 15 and unsatisfactory to carry their samples packed in casings or the like. In such case continual packing and unpacking is necessary. Such a procedure more or less injures the appearance of the goods and takes time. 20 A means for supporting the goods in display arrangement so that all that would be necessary is to open the casing and disclose the goods ready for examination by the prospective buyers would be of considerable convenience.

The general object of this invention is the provision of means in conjunction with a container for supporting goods in display arrangement so that in order to disclose the 30 goods all that is necessary is the opening of the container.

A further object of the invention is the provision of a display device provided with a plurality of supporting means for retaining the articles in display arrangement, and 35 means associated with the article supporting means for retaining them in spaced relation from one another so that they may be mounted for view in any desired position.

These objects are accomplished by providing 40 a two-piece casing similar in shape to a suit case and adapted to open outward from the center, mounting in each section of the casing means for supporting the articles in display arrangement and associating with the article supporting means means for retaining them in spaced relation to one another.

These and other objects of the invention 50 will be more clearly understood from the following detailed description and accompanying drawings.

Figure 1 is a perspective view of the display device with some articles arranged in 55 position;

Figure 2 is a top plan view of a section taken along a horizontal plane through Figure 1;

Figure 3 is a vertical section through the 60 casing shown in Figure 1;

Figure 4 is a plan view of the card adapted for retaining the article supporting means in spaced relation from one another; and

Figure 5 is a top plan view of the card 65 shown in Figure 4 folded along the dotted lines of Figure 4.

Referring to the above-mentioned drawings, a casing made up of the sections 10 and 11 hinged at 12 is shown. These sections open outward from the center. Hinged in each section 10 and 11 are frames 13 and 14, respectively. These frames might be supported in the section by any other desired method such as slidably mounting them 70 therein or attaching them therein by means of screws. Plates 15 and 16, which may be of cardboard or any other suitable material, are mounted in the frames 13 and 14, respectively. Slots 17 are provided in the 80 plates 15 and 16 and extend across the same. In this particular case the slots are made the shape of trapezoids. These slots serve to support the articles in display arrangement so that the opening of the casing discloses 85 them. Provided in conjunction with each of the plates 15 and 16 is a belt or strap 18 which serves to hold an article folded upward about the top of the card in position.

A card 19 adapted to be folded along the 90 dotted lines shown in Figure 4 is provided with projections 20 and 21 which engage in slots 22 and 23, respectively, in the plates 15 and 16. This card when placed in position with the projections engaging in the slots 95 serves to retain the garment supporting plates 15 and 16 spaced from one another. Further, when it is desired to close the casing to remove the same the card may be folded and enclosed in the casing. This 100 may also be used for displaying advertising matter or prices, as shown in Figure 1. Plates 24 and 25 are mounted in the sections 10 and 11, respectively. These plates may be used for displaying the prices or the like. 105

As shown in Figures 1 and 3, trousers 26 and 27 and 28 are supported in the section 10 by means of the plate 15. The trousers 26 are projected through the slot 17 of the plate 15 and folded as shown in the top 110

portion of Figure 3. The top portion of the trousers 26 have the belt 18 passed through belt straps so as to retain them in folded up position. The trousers 27 and 28 are also projected through the slot 17 and hung over the lower edge, as shown in the lower portion of Figure 3. Thus three pairs of trousers are supported in the one section in display arrangement so that upon 10 the opening of the casing they are displayed to view. When it is desired to permanently position the casing for display purposes, the card 19 is unfolded and the projections 20 and 21 are projected into the slots 22 and 15 23, respectively, and serve to retain the plates 15 and 16 spaced from one another, as shown in Figure 1. In this position the card serves to hold the frames 13 and 14 in position in the sections 10 and 11 of the 20 casing, respectively. In order to remove the trousers from the casing or to position them for display purposes, the frames 13 and 14 may be swung outward as they are hingedly mounted with respect to the sections 25 10 and 11.

We would state in conclusion that while the illustrated example constitutes a practical embodiment of our invention we do not limit ourselves strictly to the exact 30 details herein illustrated since manifestly the same can be considerably varied without departing from the spirit of the invention as defined in the appended claims.

Claims.

35 1. A display device of the class described comprising a two-section casing the shape

of a suit case and adapted to open outward from the center, display supporting cards mounted in each section and provided with means for supporting the articles to be displayed, and means extending between the display cards for engaging them to retain them in spaced relation to one another, said means also serving to carry the articles displayed forward out of the plane of the 45 display card.

2. In a device of the character described, for displaying articles of merchandise including a casing, a plurality of slotted plates mounted in the casing to swing about 50 the vertical axis, said plates serving to carry the articles to be displayed, and means for removably mounting between the plates to retain them in spaced relation to one another, said means also serving to carry the 55 articles displayed forward out of the plane of the slotted plates.

3. As a new article of manufacture, a device of the character described for displaying articles of merchandise, comprising a casing, a plurality of plates each having a slot extending part way across the same mounted in the casing, members attached to the top of each plate for supporting said articles in display arrangement, and means for mounting between the plates for engaging the latter to retain them in spaced relation to one another, said means serving to carry the articles displayed forward out of the plane of the plates.
